US0D1112267S

(12) **United States Design Patent** (10) **Patent No.:** **US D1,112,267 S**
(45) **Date of Patent:** **** Feb. 10, 2026**

(54) **ELECTRONIC DEVICE WITH GRAPHICAL
USER INTERFACE**

(71) Applicant: **Apple Inc.**, Cupertino, CA (US)

(72) Inventors: **Kevin Will Chen**, Cupertino, CA (US);
Nicholas D. Felton, Sunnyvale, CA (US);
Aurelio Guzmán, San Jose, CA (US);
Lauren Kim Trottier, San Jose, CA (US);
Christopher I. Wilson, San Francisco, CA (US)

(73) Assignee: **Apple Inc.**, Cupertino, CA (US)

(**) Term: **15 Years**

(21) Appl. No.: **29/914,175**

(22) Filed: **Oct. 13, 2023**

Related U.S. Application Data

(63) Continuation of application No. 29/851,439, filed on Aug. 29, 2022, now Pat. No. Des. 1,006,040, which is a continuation of application No. 29/693,368, filed on Jun. 2, 2019, now Pat. No. Des. 962,246.

(57) **CLAIM**

The ornamental design for an electronic device with graphical user interface as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an electronic device with graphical user interface showing the claimed design; and,

FIG. 2 is another embodiment thereof.

The broken lines in the figures show an electronic device and form no part of the claimed design.
